UNITED STATES PATENT OFFICE.

ROSS M. G. PHILLIPS, OF NEW HAVEN, CONNECTICUT, ASSIGNOR TO THE PHILLIPS TIME SWITCH CO., OF SHELTON, CONNECTICUT, A CORPORATION.

TIMING DEVICE.

1,375,973.

Specification of Letters Patent. Patented Apr. 26, 1921.

Application filed August 19, 1918. Serial No. 250,437.

To all whom it may concern:

Be it known that I, Ross M. G. PHILLIPS, a citizen of the United States, residing at New Haven, in the county of New Haven 5 and State of Connecticut, have invented a new and useful Improvement in Timing Devices; and I do hereby declare the following, when taken in connection with the accompanying drawings and the characters of 10 reference marked thereon, to be a full, clear, and exact description of the same, and which said drawings constitute part of this application, and represent, in—

Figure 1 a face view of a timing mechanism constructed in accordance with my invention, and partly broken away.

Fig. 2 a side view of the same.

Fig. 3 an inside view of the outer plate of the timing mechanism illustrating the operating lever and showing the connection with the valve mechanism, and also showing the timing mechanism.

Fig. 4 a side view of the same showing a vertical sectional view of the valve mechanism.

Fig. 5 an underside view of the valve.

Fig. 6 a modification.

Fig. 7 a sectional view on the line 7—7 of Fig. 3.

Fig. 8 a perspective view of the firing cam, detached.

This invention relates to an improvement in timing devices such as are used in controlling the time which an apparatus, such, 35 for instance, as gas stoves, water heaters, etc., shall operate. These devices are arranged closely adjacent to the apparatus which they control, but it is often desirable to set them in operation from a distant 40 point, as for instance, to set a timing device in the kitchen from a room on the floor above.

The object of this invention is to provide a timing device with means for setting it 45 for predetermined intervals from a point distant from the apparatus, and the invention consists in a timing device having certain details of construction as will be hereinafter described and pointed out in the 50 claims.

In carrying out my invention as herein shown, the stem 28 of the valve plug 29 has connected to it a valve lever 27 to which is pivoted the finger 25 of the cocking link 14 which is thereby connected with the gas-

cock handle 40 for operation thereby. The valve plug 29 is seated in a valve-casing 30 and controls the passage 31 thereof, this valve being connected with the gas pipe 32 from the source of supply, and with the gas 60 pipe 33 leading to the burner. As herein shown, the valve casing is formed at opposite ends with upward projections 34 and 35 the inner walls of which are formed with slots 36 and 37 to receive the ends of the 65 spring locking plate 38 which is set over the valve stem 28 and rests on a spring 39 around the valve stem and bearing upon the valve lever 27 so as to force the valve plug to its seat. The valve stem may be provided with a handle 40 by which the valve 70 may be manually operated. The valve casing is secured to the plate 20 by screws 48 and 93.

The upper end of the cocking link 14 is 75 formed with a slot 15 in one side of which is a notch 16 forming a cocking shoulder 17. Projecting through this slot is a flat pin or stud 18 fixed to a plate 19 which is secured to the inner face of the front plate 20 of 80 the casing 10 by a screw 88. As herein shown the plate 19 is formed with a notch 21 through which a screw 22 extends. A nut 23 on the screw 22 bears upon the plate to hold it in place. The cocking lever 14 is 85 normally moved upward under pressure of a spring 26 one end of which is fixed to the screw 22 and the other end to a finger 24 projecting outward from one side of the cocking lever 14. The cocking lever extends 90 into the path of the firing cam 13 formed at the rear end of a hub 61 which projects forward through the front plate 20 of the casing, the projecting forward end of the hub 61 having a square shoulder 62 which is entered into a square opening 63 formed in the upper end of a setting lever 11 which is furnished at its lower end with a handle 64 and at its upper end with a pointer 65 which sweeps over graduations upon a dial 100 66 secured to the outer face of the front plate 20 of the casing 10 by means of the screw 22 and by means of screws 67 which extend through the front plate 20 of the casing 10 into engagement with the front plate 105 68 of the timing mechanism, whereby both the dial and timing mechanism are secured in place, the dial also being secured to the front plate 20 by a screw 89, and the front plate 68 of the timing mechanism also being 110

secured by screws 90 and 91. The said hub 61 is formed with a square opening 69 for the reception of the squared forward end 70 of the winding arbor 12 which is journaled 5 in the front and rear plates 68 and 71 of the ordinary clock movement of any preferred construction. A cap nut 72 secured upon the extreme forward end of the arbor 12 holds the setting lever 11 in place upon 10 the square shoulder 62 of the hub 61 of the firing cam 13. Loosely mounted upon the arbor 12 is a main wheel 73 which meshes into a pinion 74 upon the arbor 75 of the escapement train which may be of any approved construction and which it is unnecessary to describe in detail. The said main wheel 73 carries a spring-actuated 15 pawl 76 engaging with the teeth of a ratchet wheel 77 loosely mounted upon the arbor 12 20 and bearing directly upon the front face of the main wheel 73 against which it is pressed by a coupling or friction disk 78 non-rotatably mounted upon the arbor 12 but longitudinally movable thereupon, and 25 pressed against the said ratchet wheel 77 by a spring 79 encircling the said arbor and abutting at its outer end against a nut 80 mounted upon the threaded portion of the said arbor 12 whereby the tension of the 30 spring 79 may be adjusted as desired, to increase or decrease the friction between the friction disk 78 and the ratchet wheel 77. The tension of the spring 79 must be sufficient to crowd the disk 78 against the ratchet 35 wheel 77 so as to develop the friction required to couple them for rotation together when the setting lever 11 is turned counter-clockwise for concurrently winding the main spring 81 of the setting and timing mechanism. In resetting the mechanism to 40 shorten the period to which it was set and to correspondingly unwind the main spring 81, the lever 11 is turned clockwise against the friction developed by the spring 79 between 45 the disk 78 and the ratchet wheel 77, which latter is then held against rotation by the pawl 76, while the main spring is unwound and the pointer 65 swept clockwise over the dial 66. The said spring 79 and the parts 50 co-acting therewith, thus form means for frictionally coupling the winding arbor 12 with a member of the escapement train of the clock movement, whereby the setting lever 11 may operate to unwind the main spring 81 after the mechanism has been initially set.

Fixed to the hub 61 outside the front plate 20 is a ratchet 41, and moving in the path of this ratchet is a long pawl 42 the 60 lower end of which is pivotally connected with the cam plate 43, which is formed with a segmental collar 44 extending over the valve stem 28, the ends 45 and 46 of the collar arranged to be engaged by the handle 65 40. A spring 47 tends to draw the cam

plate 43 to its normal position against a sleeve 94 on the screw 48, while a spring 49 connected to one end 50 of the pawl and to the front plate 20, tends to force the pawl into engagement with the ratchet 41. The 7 teeth on the ratchet are so proportioned and arranged that for each movement of the cam plate the ratchet will be moved one step so as to turn the setting lever 11 to a predetermined distance as for instance, so that 75 the timing mechanism will run for ten minutes at the expiration of which time the firing cam 13 will move the cocking link 14 so as to move the cocking shoulder 17 out of engagement with the stud 18 allowing the 80 cocking link 14 to move downward to close the valve.

Assuming that the device is used in connection with a water heater, and it is desired to have the burner turned on for ten 85 minutes, the operator will pull a wire or chain 82 connected with a lever 83 to the limit of its movement. This lever 83 which is adjustably connected with cam plate 43 by a screw 84 entering a hole 92 in the cam 90 plate, will turn the cam plate 43, and the end 45 of the collar 44 bearing against the handle 40 will open the valve in the gas supply pipe and push the pawl 42 upward so that its upper end engaging with the 95 ratchet 41 will move that ratchet one step forward and turn the setting lever accordingly and start the timing mechanism. By the movement of the cam lever 43 in opening the valve, the cocking link 14 is drawn 100 downward so that the shoulder 17 engages with the flat pin 18 by which the cocking link is locked in its down position and the valve in the pipe held in the open position. The spring 47 tends to hold the lever against 105 the pin 18. When the cord or chain 82 is released the cam plate 43 returns to its normal position under the action of the spring 47. At the expiration of ten minutes, or a predetermined time, the firing cam 13 on the 110 arbor 12 will come into contact with the cocking link 14 and push it to one side so as to clear the pin 18 permitting the spring 26 to draw the cocking link 14 upward and turn the valve to close the passage in the 115 pipe by causing the end 46 of the collar to engage with the handle 40. If it is desired to have the gas turned on for twenty minutes, the cam plate 43 will be moved twice; if thirty minutes, three times, and so on. It 120 will thus be seen that the timing device may be set at any predetermined interval at a point distant from the timing device itself.

Instead of using a pawl and ratchet to operate the arbor 12, I may use any known 125 form of clutch mechanism. Thus as shown in Fig. 6 of the drawings, I may loosely mount a cam disk 85 on the arbor 12 in each of the notches 86 of which I place a ball 87. An arm 88 on the cam disk 85 will be con- 130

nected by a link 95 with the cam plate 43. In this case the spring 49 will not be required. As also indicated in Fig. 6 the lever 83 is in position to be moved by an upward 5 pull upon a chain 89. The particular advantage of the valve construction shown is the convenience of assembling the parts as it is only necessary to compress the ends of the spring plate 38 and turn it so as to turn 10 the ends out of engagement with the notches 36 and 37 to permit the valve plug 29 to be removed from its seat.

I claim:—

1. In a timing device, the combination 15 with the arbor of a time movement, of a cam operated thereby, a cocking link arranged in the path of said cam, said link formed with a shoulder near its upper end and with a finger near its lower end, a stud 20 with which said shoulder will engage, and a spring tending to raise the link and throw it into engagement with the said stud.

2. In a timing device, the combination 25 with the arbor of a time movement, of a cam thereon, a cocking link arranged in the path of said cam, said link formed with a shoulder, an adjustable stud with which said shoulder will engage, means for drawing the link downward, and a spring tending to 30 raise the link and throw it into engagement with the said stud.

3. In a timing device, the combination 35 with the arbor of a timing movement, of a cam thereon, a vertically movable cocking link arranged in the path of said cam, said link formed with a slot, a notch in said slot forming a shoulder, a stud with which said shoulder will engage, means for drawing the link downward, and a spring tending to 40 raise the link and throw it into engagement with said stud and move the lever upward.

4. In a timing device, the combination 45 with the arbor of a time movement, a cam on said shaft, a cocking link in the path of said cam and adapted to be moved thereby, a valve stem connected with the lower end of the said link, a cam-plate mounted on said valve stem and adapted to move the same, a ratchet mounted on said arbor, a pawl connected with said cam-plate and adapted to 50 turn said ratchet, and means for turning said cam-plate.

5. A timing device comprising timing 55 mechanism, an arbor for starting the timing mechanism in operation, a cam on said arbor, a cocking link in the path of said cam

and adapted to be operated at the completion of a predetermined movement of the arbor, a valve connected with the lower end of the link and operated thereby, means for locking the link in its valve-opening position, a cam-plate mounted on the stem of said valve and adapted to turn the same, and means operated by the movement of said cam-plate for turning the arbor. 65

6. A timing device comprising timing mechanism, an arbor for starting the timing mechanism in operation, a cam on said arbor, a cocking link in the path of said cam and adapted to be operated at the completion of a predetermined movement of the arbor, a valve connected with the lower end of the link and operated thereby, means for locking the link in its valve-opening position, a ratchet on said arbor, a pawl in the 70 path of said ratchet, the pawl being pivotally connected with said cam-plate, a lever connected with said cam-plate, and means for operating the said lever from a point distant from the timing mechanism. 75

7. In a timing device, the combination 80 with an arbor, a cam on said arbor, a cocking link in the path of said cam and adapted to be moved thereby, a valve stem connected with the lower end of said link, and operating mechanism attached to the valve stem and engaging with the arbor whereby the valve is opened and the arbor set for a predetermined time by the movement of the operating mechanism. 85

8. In a timing device, the combination 90 with an arbor, a cam on said arbor, a cocking link in the path of said cam and adapted to be moved thereby, a valve stem connected with the lower end of said link, operating mechanism attached to the valve stem and engaging with the arbor whereby the valve is opened and the arbor set for a predetermined time by the movement of the operating mechanism, and means for returning the operating mechanism to its normal position whereby each additional movement of said mechanism extends the predetermined time of return movement of the arbor. 95

In testimony whereof, I have signed this 100 specification in the presence of two subscribing witnesses.
